UNITED STATES PATENT OFFICE.

FRED HARRIS LYNDS, OF NORTH ATTLEBORO, MASSACHUSETTS, ASSIGNOR TO WHITING & DAVIS COMPANY, A CORPORATION OF MASSACHUSETTS.

SUPPORT FOR LINK-MESH FABRIC.

Application filed June 17, 1921. Serial No. 478,236.

To all whom it may concern:

Be it known that I, FRED HARRIS LYNDS, a citizen of the United States, residing at North Attleboro, in the county of Bristol, 5 State of Massachusetts, have invented certain new and useful Improvements in Supports for Link-Mesh Fabric; and I do hereby declare the following to be a full, clear, and exact description of the invention, such 10 as will enable others skilled in the art to which it appertains to make and use the same.

This invention relates to a device for supporting link mesh fabric, as for example, in 15 a machine to feed the fabric to tools and hold it in position while the latter operate on the fabric to perform their functions.

In machines for making link mesh fabric, whether in the flat or in the form of a 20 sleeve, a support is provided for holding the fabric and feeding it to dies or link forming tools, usually in a step by step movement, to present successive rows of links to the tools for the addition of new rows of links 25 in the making of the fabric. The links of the fabric to which new links are added must be accurately positioned in the path of the tools, and this necessitates providing the support with some means for preventing 30 shifting of the fabric, not only during the feeding movement but also while the link forming tools operate to form links and add them to the fabric. It has heretofore been the practice to provide the face 35 of the support with such means to prevent relative movement between the support and the mesh fabric, or the shifting of the latter, consisting of rows of ridges and depressions extending in straight lines 40 across the face of the support. Thus, in machines of the character wherein the link mesh is made in the form of a sleeve, illustrated and described, for example, in Letters Patent Nos. 948,615, 1,028,904 and 45 1,144,724, issued Feb. 8, 1910, June 11, 1912, and June 29, 1915, respectively, to A. C. Pratt, the mesh fabric is supported on a mandrel, the face or surface of which is fluted, or in other words, provided with alternate rows of ridges and depressions 50 extending in straight lines longitudinally of the mandrel. Also in machines for performing various other operations on link mesh fabric, such for instance as link mesh meas-

uring machines, machines for cutting out 55 shapes or articles from mesh fabric, as for instance link mesh bags, or machines for mending link mesh, supports for the fabric are required, and in order that the fabric may be firmly gripped and accurately fed 60 to the tools for performing these operations, it is essential that the face of the support be provided with means for preventing relative movement between the fabric and the support. 65

The support for the fabric in the various machines above specified is usually in the form of a roll, and it has heretofore been the practice to provide the face of the roll with rows of depressions alternating with 70 rows of ridges extending in straight lines axially of the roll, or for example, projecting pins to grip the fabric; and, where supports have been employed having faces provided with such ridges and depressions, it 75 has been common to employ pressure rollers to hold the fabric against the face of the support to insure interlocking engagement between the fabric and the roll. Such gripping devices have, in the main, proven quite 80 satisfactory, but whether for use in a machine for making link mesh, or in machines where even greater firmness of support and precision in feeding the fabric are desirable, as in link measuring, cutting or mending 85 machines, a support made in accordance with the present invention has been found to be more dependable and to give more uniform and accurate results.

In accordance with this invention the 90 face of the support for receiving the link mesh fabric is cut to simulate the surface of the link mesh so that the fabric is gripped by the face of the support and firmly held against movement relative to it, or 95 shifting in any direction. The face of the support, the latter usually being in the form of a cylinder or roll, is provided with a plurality of depressions extending in rows 100 across the support, the depressions preferably being curved and also having laterally extending branches therefrom to receive portions of the links of the fabric. In one arrangement, the depressions are inter-connected to form grooves across the support 105 which are separated by ridges, the grooves and ridges being complementary to the ridges and depressions formed by the links of the

fabric. Since successive rows of links of the fabric are oppositely inclined, usually at an angle of about 45° , the depressions in the face of the support are preferably 5 undercut or inclined to the face of the support, alternate rows of depressions being oppositely inclined in this manner to correspond to the inclinations of the links of the fabric. Thus the face or surface of the support is covered with a multiplicity of receptacles for receiving a portion of each of the links of the fabric across its width and over the area of contact between the fabric and the support. When the mesh fabric is 10 laid upon the support and moved across its face, portions of the links enter the grooves formed by the depressions and lodge in the inclined depressions or receptacles which firmly grip the links and hold the fabric against any movement relative to the support, and thus there can be no shifting of the fabric as it is fed forward, for example, to tools for forming links, or cutting them or for any other operation which may 15 be performed on the fabric.

The invention is illustrated in the accompanying drawings, in which

Figure 1 represents a roll for supporting a piece of link mesh fabric, a portion of the 20 face of which is shown bearing an impression of the surface of the fabric;

Figure 2 is a cross sectional view of the roll shown in Figure 1, along the line 2—2;

Figure 3 is a cross sectional view of the 25 roll along the line 3—3 of Figure 1;

Figure 4 represents a piece of link mesh fabric on an enlarged scale;

Figure 5 represents a development of the 30 gripping means on the roll shown on an enlarged scale;

Figure 6 is a view along the line 6—6 of Figure 5, and

Figure 7 is a view along the line 7—7 of 35 Figure 5.

Figure 1 represents a cylinder or roll 8 such as is commonly used in link mesh machines for supporting a piece of link mesh fabric 9 and feeding the links thereof to tools for carrying out various operations, 40 such as the formation of links, or the cutting, measuring and mending of links. The face 10 of the roll is provided with gripping means 11 to prevent slipping, or movement of the link mesh fabric relative to the roll, 45 on which it is supported. The gripping means 11, a small portion of which is illustrated in Figure 1, covers the entire surface of the roll, its width being usually equal to the width of the mesh fabric which the roll

50 is to carry, and consists of a plurality of curved depressions interconnected to form grooves 12 which are separated by ridges 13 thus simulating the surface presented by the link mesh fabric. The grooves 12 are cut 55 in the face of the roll at an angle of ap-

proximately 45° to normal, as illustrated in Figures 2 and 3, corresponding to the inclinations of the links of the fabric, alternate rows of grooves being oppositely inclined in the same manner as alternate rows of links. 70

The formation of the grooves 12 and ridges 13 is illustrated on an enlarged scale in Figure 5, representing an impression of the link mesh fabric cut in the surface of a flat plate that may serve as a support for holding the fabric while any desired operation is performed. Figure 5 serves to illustrate a development of the gripping means 11 on the face of the roll 8. 75

As shown in Figure 5 the grooves 12 and ridges 13 are of a formation such as to simulate the surface of the piece of link mesh fabric represented in Figure 4. The grooves 12 may be considered to consist of a plurality of curved link receptacles 14 having laterally extending branches 15 for receiving portions of each of the links. As illustrated in Figure 6, the links of the section of mesh fabric represented in Figure 4, along the line 6—6, are inclined in one direction as shown. In Figure 6 the links along the line 6—6 are represented in place in the grooves 12, each link fitting in one of the curved, inclined link receptacles 14 and its branches 15. As shown in Figure 7, the links of the section of link mesh in Figure 4, along the line 7—7, are inclined in the opposite direction, and Figure 7 represents the links along this line in position in the grooves 12 which are inclined oppositely to the grooves in Figure 6 to correspond to the inclination of the links of this row, the individual links being shown in place in their respective link receptacles 14 and branches 15. 80

It will be evident that if the section of mesh fabric shown in Figure 4 is placed on the face of the flat plate shown in Figure 5, and the mesh is moved or adjusted slightly over the face of the plate, the various rows of links will enter the grooves 12, and the individual links of each row will enter the various link receptacles 14, each of the latter receiving a portion of a link thus firmly gripping the fabric to resist relative movement between the fabric and the plate. 90

I claim:

1. A support for a piece of link mesh fabric having a face for receiving the link mesh which is cut to simulate the surface of the link mesh thereby to grip the latter and resist relative movement between the fabric and the support. 100

2. A support for a piece of link mesh fabric having a face provided with a plurality of depressions each curved in semi-circular form to correspond to the links of the fabric and forming receptacles for the latter. 105

3. A support for a piece of link mesh 110

fabric having a face provided with a plurality of depressions each curved in ring-like form to correspond to the links of the fabric and arranged in rows across the support for receiving the links, substantially as described.

4. A support for a piece of link mesh fabric having a face provided with a plurality of ring-shaped depressions connected together to form grooves across the support.

5. A support for a piece of link mesh fabric having a face provided with a plurality of semi-circular depressions simulating the surface of the fabric for receiving links of the fabric.

6. A support for a piece of link mesh fabric having a face for receiving the link mesh which is provided with a plurality of semi-circular depressions interconnected to form grooves across the support alternating with ridges, said grooves and ridges being complementary to the ridges and depressions formed by the links of the fabric.

25 7. A support for a piece of link mesh fabric having a face provided with depressions arranged in rows across the support, each depression of each row being adapted to receive a portion of a link, said depressions being formed to simulate the surface of the fabric.

30 8. A support for a piece of link mesh fabric having a face provided with depressions arranged in rows across the support, each depression of each row having

branches extending laterally therefrom and being adapted to receive a portion of a link.

9. A support for a piece of link mesh fabric having a face which is provided with a plurality of grooves cut at an angle to the 40 surface of the support to correspond with the inclination of the links of the fabric.

10. A support for a piece of link mesh fabric having a face provided with a plurality of curved depressions for receiving 45 links of the fabric, said depressions being cut at an angle to the surface of the support corresponding to the inclination of the links.

11. A support for a piece of link mesh 50 fabric having a face provided with a plurality of curved depressions interconnected to form grooves across the support, alternate grooves being oppositely inclined to the face of the support to correspond to the 55 inclination of the links of the fabric.

12. A support for a piece of link mesh fabric having a face provided with a plurality of curved depressions having laterally extending branches therefrom, said 60 depressions and branches being arranged across the support forming a plurality of rows of link receptacles for receiving portions of the links of the fabric thereby to grip the latter and resist relative movement 65 between the fabric and the support.

In testimony whereof I affix my signature.

FRED HARRIS LYNDS.
